Major Pratt H C
Design for stone

Des. 437

James Wager, David Pratt, and Volney Richmond, of the City of New York,
Letters Patent No 437. Dated Jan 10th 1852.

The schedule referred to in these Letters Patent and making part of the same.

To all to whom these presents shall come,

Be it known that we,

James Wager, David Pratt, and Volney Richmond, of the City of New York,
and County of Rensselaer in the State of New York have invented or
produced, a certain new design for Parlor Stoves, and that the following
is a full, clear, and exact description of the character which distinguishes it
from all other things before known reference being had to the accompanying
drawings making part of these specifications. Fig 1 showing our
design as applied to an open front or Franklin Parlor Stove to consist
of certain ornamented plates of peculiar shape and configuration to,

suit the purpose of the stone to which it is attached. The form and shape of the Urn A in Fig 1 is clearly shown in the drawing, the body of which is fluted and the vertical section of the cover is an O. B, and the horizontal section is composed of coves and beads separated by fillets, and the top of cover represents pointed water leaves. The top plate of the stove is raised in the centre C resembling a pediment and has fillet and O.L mouldings around the outer edge. At each end of this plate is a raised Gothic pannel ornamented in the centre and ~~at~~ the middle section of the top B has an octagonal projection which forms the base upon which the Urn stands and the upper section of this base E has at each angle a shell ornament.

The tops of the four plates forming the body of the stove have a heavy cove moulding F which is relieved with ball flower ornaments. These four plates forming the body of the stove where they come together and make the corners have clustered Gothic double columns H. Directly under the mouldings at the top of the stove is shown heavy netrile work G. In Fig 1 is a false moveable hearth of elliptical form, the front of which has cove and bead work separated by fillets the inside projection being formed of angular flutes. K in Fig 1 shows the form of the leg which is ornamented with a stem of budding flower. L shows the bottom flut of the stove ornamented around the edge with oval O cove and fillet work. At each corner of this plate or directly over the leg is a star ornament upon an octagonal base or plinth I in Fig 1 represents a front fender directly over the grate and which is ornamented with interlaced semicircular arches. The two end plates J of the stove are ornamented with two Gothic panels supported by a corbel and the heads of which are formed of Gothic tracery. Fig 2 represents a clover or detached plate which closes or shuts the space over grate and is ornamented with oval O work and three Turkish domes. Fig 3 represents a back plate used in same stove the top and side portions of which corresponding with the open front in Fig 1. The middle portion of this plate M has a sunk panel in which is a scroll and fan light ornament. This panel is surrounded with heavy cove and oval O moulding under this panel and between the two corner columns are four quatrefoil panels N and two dwarf columns O. Between the centre panels and side column are acanthus leaf ornaments hanging downwards.
